UNITED STATES PATENT OFFICE.

JOSEPH BIANCHI AND LOUISE A. BIANCHI, OF CHICAGO, ILLINOIS.

OIL BURNER.

Application filed March 26, 1923. Serial No. 627,573.

To all whom it may concern:

Be it known that we, JOSEPH BIANCHI and LOUISE A. BIANCHI, citizens of the United States, and residents of the city of Chicago, county of Cook, and State of Illinois, have invented certain new and useful Improvements in Oil Burners, of which the following is a specification.

Our invention relates to novel improvements in oil burners and has for its principal object the provision of an improved construction of this character which will be highly efficient in use and economical in manufacture.

Another object of the invention is the provision of introducing air into the burner so as to increase the intensity of the heat and at the same time create a draught so that there will at all times be a uniform circulation of the air through the burner.

Other objects will appear hereinafter.

The invention consists in the combinations and arrangements of parts hereinafter described and claimed.

The invention will be best understood by reference to the accompanying drawings forming a part of this specification and in which,

Fig. 1, is a sectional view of a burner embodying the invention;

Fig. 2, is a sectional view taken substantially on line 2—2 of Fig. 1, and

Fig. 3, is a fragmentary view of the wick embodied in the invention.

Referring to the drawings showing the preferred form of construction "A" indicates the burner embodying the invention comprising a hollow body 10 having a horizontal partition 11 provided with a central opening 12 surrounded by an annular flange 13. The partition 11 divides the body into two compartments one above the other indicated at 14 and 15. Communicating with the lower compartment 15 is a cavity 16 formed in a lateral extension 17, located adjacent the bottom of the body, the cavity 16 being adapted to permit the introduction of air into the compartment 15. Communicating with the compartment 14 is a supply

pipe 18 having an inlet located in the side wall of the body below the edges 20 of the annular flange 13, for the delivery of fluid to the compartment. Surrounding the inner side walls 21 of the compartment 14 is an asbestos wick 22 having a portion cover-

ing the inlet 19 so that the wick will readily absorb the fluid passing into the compartment 14. The surfaces of the wick adjacent the walls 21 are covered by a perforated band 14', the purposes of which are to permit penetration of the fluid into the wick and also to permit the fluid to flow between the band and the wall and penetrate into the wick through the various perforations of the band. A cap 23 having a central opening 24 and openings 25 radially disposed about the central opening 24 is carried by the annular flange 13, the cap 23 being an inverted, dish-shaped member so that the radially disposed openings 25 will discharge the air from the compartment 15 in diverged directions with respect to the air passing through the central opening 24, the direction of the air through these openings 24 being indicated by arrows in Fig. 1. It will be seen that by forming the cap in the manner above described that the flame of the burner is spread outwardly so as to cover a large surface.

A closure 26 is provided for the open top 27 of the body and is provided with a central opening 28 of a diameter substantially equal to the outside diameter of the annular flange 13, the peripheral edges of the closure 26 being set in recesses 29 formed in the side walls 29 of the body.

In use, the asbestos wick 22 is ignited in any manner desirable and the heat radiated therefrom and the flame thereof passes through the opening 28 of the closure 26 and at the same time air is being introduced into the air compartment 15 through the cavity 16 and is drawn up through the opening 12, and the several openings of the cap 23 commingling with the flame of the wick spreading the flame so as to cover a large surface of the apparatus with which the burner is used; this spreading of the flame is accomplished as stated, by diverging the incoming air in several directions through the radially disposed openings 25.

The burner may be of any other configuration than that shown and of any size or proportion without destroying the utility of the invention, it being borne in mind that by the construction of a burner as herein set forth the area of the surface heated by the burner is greatly increased by the provision of the several openings formed in the dish-shaped cap 23. It will also be appar-

ent that by providing an air compartment below the combustion compartment, the incoming air through the cavity 16, and the air compartment, as it passes up through the opening 12 will be heated so that by the time the air passes through the several openings of the cap the air is of a higher temperature than that passing through the cavity into the compartment 15. Still further it will be apparent that as the heated air passes with the flames through the closure opening a suction will be provided as the incoming air is introduced through the opening from below the combustion compartment and will assure a uniform circulation of air.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having described our invention what we claim as new and desire to secure by Letters Patent is:

30 1. A burner of the class described including a body having a partition dividing the body into two compartments, an extension having a cavity communicating with one of said compartments for the introduction of air thereto, flanged means formed in said partition providing an opening, and an inverted dish-shaped perforated cover mounted over said opening to direct the air from the air compartment in various directions 40 in the other compartment.

2. A burner of the class described including a hollow body having a cross partition with an opening and forming communicating compartments, a supply pipe for delivering fluid to one of the compartments, a wick in the compartment having a portion covering the inlet of the supply pipe and adapted to absorb the fluid passing therethrough, and an extension having a cavity 45 communicating with the other compartment for delivery of air thereto, said air being adapted to pass from said compartment

through the other compartment and commingle with the flames of the burning fluid.

3. A burner of the class described including a body having a partition dividing the body into an upper and lower compartment, said partition having a central opening surrounded by an annular flange extending into the upper compartment, an extension having a cavity communicating with the lower compartment for the introduction of air thereto, and a perforated dish-shaped member carried by the annular flange adapted to direct the air in various directions passing from the lower compartment through the upper compartment.

4. A burner of the class described including a body having a partition dividing the body into an upper and lower compartment, 70 said partition having a central opening surrounded by an annular flange extending into the upper compartment, a wick mounted in the upper compartment, an extension having a cavity communicating with the lower compartment for the introduction of air thereto, and an inverted dish-shaped perforated member carried by the flange adapted to direct the air passing from the lower compartment through the upper compartment 80 in various directions.

5. A burner of the class described including a body, a partition dividing the body into an upper and lower compartment, the lower compartment having an extension provided with a cavity for the introduction of air thereto, there being an opening in the partition surrounded by an annular flange, a dish-shaped member carried by the flange and provided with a central opening and 90 radially disposed openings about said central opening, a wick arranged in the upper compartment, a closure member for the upper compartment having an opening above the opening of the partition.

In testimony whereof we have signed our names to this specification in the presence of two subscribing witnesses.

JOSEPH BIANCHI.
LOUISE A. BIANCHI.
